Primary Examiner — Dana L Meyrow(74) *Attorney, Agent, or Firm* — Parks Wood LLC(57) **CLAIM**

We claim the ornamental design for a bottle, as shown and described.

DESCRIPTION

FIG. 1 is a perspective view of a bottle in accordance with our new design;

FIG. 2 is a right side elevation view thereof;

FIG. 3 is a left side elevation view thereof;

FIG. 4 is a front elevation view thereof;

FIG. 5 is a rear elevation view thereof; and,

FIG. 6 is a top plan view thereof.

The evenly-dashed broken lines in the drawings illustrate the portions of the bottle that form no part of the claim. The dot-dot-dash broken lines in the drawings define the bounds of the claim and form no part thereof.
